SECTIONAL BOILER

Application filed February 6, 1930. Serial No. 426,205.

This invention relates to hot water and steam boilers of the sectional type and provides by means of a novel construction new advantages in the transfer of heat from the flue gases to the heated medium and new advantages in the manufacture and maintenance of the boilers.

This invention constitutes an improvement over the prior application of Charles A. 10 Olson, Serial No. 301,527, filed August 23, 1928, the improvement consisting in the use of a new and improved steam dome. By means of this improved steam dome, which is provided with a smoke outlet at the rear 15 of the boiler and which avoids the use of the top outlet for the smoke, the former height of the boiler is held at a minimum.

A further object is to prevent stagnation 20 of the flue gases in the flue passage beneath the dome which would otherwise impede if not destroy the slight draft resulting from banked or low firing. This result is accomplished by maintaining this flue passage of substantially constant cross sectional area 25 throughout its length notwithstanding the variation in its width occasioned by the circular contour of the boiler.

Another advantage provided as an object 30 of this invention is a maximum downwardly facing heat transfer area in the dome section under which the hot gases must flow on their way to the smoke outlet.

Another object of this invention is the provision of a steam dome which can be 35 made as a very simple casting requiring no small cores, and also requiring the minimum amount of metal per unit area of downwardly facing heat transfer surface.

The importance of providing as much of 40 the downwardly facing heat transfer surface under which flue gases flow, above which the water to be heated is retained, is that using such a surface heat is transferred much more efficiently from flue gases to the 45 water than where vertical surfaces are employed or where upwardly facing surfaces having gas above them and water below them are employed.

Furthermore, another advantage arises in 50 the fact that all of the heat transfer sur-

faces employed in this boiler are easily cleaned and no pockets of substantial size exist therein in which soot may accumulate or which may form dead air spaces for the flue gases.

Other objects and advantages of this invention should become apparent upon perusal of this specification and the drawings forming a part thereof.

In the drawings:

Fig. 1 is a central vertical sectional view of a boiler embodying this invention;

Fig. 2 is a plan view of one of the intermediate sections of the boiler;

Fig. 3 is a vertical section on the line 65 3-3 of Fig. 2;

Fig. 4 is a plan view of the dome section; and

Fig. 5 is a partial sectional view, the section being taken on the line 5-5 of Fig. 4. 70

In the drawings the boiler is shown as comprising a base 1, a fire-box 2 and four intermediate boiler sections 3, 4, 5, and 6, these being surmounted by a steam dome generally indicated as 7.

The grate bar and ash pit construction form no part of this invention, hence require no detailed description.

The fire-box is preferably provided with an annular water jacket 8 which extends 80 entirely around the fire-box, excepting at the apertures at which are located the clinker door 9 and the feed door 11. The water is introduced into this fire-box water jacket through a pipe 12 and it then flows upwardly through the water jacket and passes through a pair of ports similar to the ports 13 which are provided in the intermediate section shown in Fig. 2.

Each of the intermediate sections is constructed in important respects like the intermediate sections shown in Figs. 2 and 3, the difference between them existing only in the provision of the aperture at which is located the flue cleaning door 14, that is, each 95 intermediate section is provided with a vertical flue aperture substantially like the aperture 15 shown in Fig. 2, adjacent to which are ports similar to the ports 13 admitting water from below. The water then is con- 100

ducted from these water inlets at the bottom of each section through the marginal portions 16 and 17 of the water chambers into the main portion 18 of the water chamber of the section and thence flows to the two upwardly extending water outlets 19.

The water inlets of the lowermost section are placed in registry with a pair of water outlets in the fire-box section, one of which 10 outlets 22 is shown located in an enlarged wall portion 23 of the fire-box section. The water inlet of the first intermediate section is held in water tight registry with the outlet 22 by means of the push nipple 24. Accordingly, it will be understood that each 15 of the two water outlets 19 of each of the intermediate sections 3, 4 and 5 is placed in registry with the water inlets 13 of the sections which respectively lie above them. The 20 water outlets 19 of the top intermediate section 6 are connected with the water inlets 25 of the dome section 7, thus conveying the water into the large chamber 26 in the dome section from which it may be conducted into the heating system.

The flue gases flow from the fire-box upwardly against the downwardly facing surface of the first intermediate section, which surface corresponds to the horizontal wall 30 27 shown in Fig. 3. The flue gases then flow through the first vertical flue aperture which corresponds to the aperture 15 shown in Fig. 2 and 3, thence above the water chamber 18 of the first section and below 35 the corresponding horizontal water chamber 18 of the second intermediate section until the flue gases reach the second vertical flue such as the flue 15 and continue their upward course. It will be observed that the 40 flue gases are thus caused to traverse under each downwardly facing lower wall of the horizontal water chambers 18, thence through the vertical flue 15 in each section and are then caused to repeat the same 45 course under and through the succeeding boiler sections which lie thereabove. Eventually the flue gases emerge from the uppermost horizontal section 6 under the lower wall 28 of the steam dome where these gases 50 once more contact with an upwardly facing heat transfer surface imparting to the water thereabove retained their heat units with maximum efficiency. The flue gases are then thereafter conducted through the 55 smoke outlet 29 and are carried off through a smoke outlet not shown.

The flue passage immediately beneath the water chamber of the dome is obviously of varying width because of the outer curvature of its side walls. To maintain a substantially uniform cross section of this passage from inlet to outlet so as to obviate stagnation of the gases therein, the depth 60 of the passage is varied inversely to but 65 commensurately with the variation in width.

This variation in depth is accomplished in the present instance by downwardly curving the upper wall 28 from its ends towards its center as shown proportionately with the outward curvature of the side walls.

70

This curved contour of the wall 28 in addition to equalizing the cross sectional area of the underlying flue passage from inlet to outlet also increases the heat transferring area of said wall.

75

Both the water and flue gases travel continuously in a generally upward direction and each traverse as nearly as possible the entire horizontal width of their respective passages through each boiler section until the flue gases emerge through the outlet 29 and the water is carried upwardly through its outlet port 31. The water passages of the adjacent boiler sections are suitably connected by means of push nipples such as the push nipple 24 while the flue passages of the several sections are readily connected by placing the sections one above the other. The margins of the flue passages at the exterior of the boiler are sealed by cooperating 80 ribs such as ribs 32, 33 and 34.

85

All of the area of the steam dome which is exposed to the flue gases is a downwardly facing area which therefore provides the best conditions for the maximum transfer of heat from the flue gases to the water. Furthermore, since no attempt is made to conduct the flue gases upwardly through the dome section there is no necessity for providing any vertically walled passages for delivering the flue gases upwardly. It is desirable to eliminate such vertical walls as they are not efficient heat transfer surfaces and while they do add considerably to the cost of metal required in the casting they 95 do not increase the efficiency of the boiler. Furthermore, with a dome section designed as shown in the drawings no small cores are required for its casting which is therefore a considerable advantage from the manufacturing standpoint and this advantage is obtainable along with the advantages of increased heat transfer efficiency. In order to properly brace this heat transfer surface 100 of the dome section a plurality of spacing rods 35 are cast connecting the upper and lower walls of the dome section to prevent 105 warping thereof.

110

It will be noted that the flue gases issuing 115 from the fire-box are conducted in a single stream flowing continuously to the smoke outlet. By retaining these gases in a single stream their stratification into layers of different temperatures is thus more readily prevented and it is found from experiments 120 that a higher efficiency of heat transfer is thus obtained. Furthermore, a substantially constant flue area is provided throughout all of the boiler sections which contributes 125 to the maintaining of constant velocity of 130

the flue gases and constant contact of the gas with the flue walls.

The bosses 38 with which the dome section is provided and two of which surround the water inlet apertures 25, are provided on their top surfaces with flat shoulders such as the shoulder 39 shown in Fig. 5. When the furnace man is assembling this boiler and has placed all of the sections in proper position he utilizes the shoulders 39 for hammering the sections down one upon the other to assure the tight fitting of the push nipples. These bosses being directly above the push nipples serve to transmit the force of the blows directly down upon the entire assemblage of push nipples.

This arrangement of intermediate sections and dome section is such that obviously the contour of the water chambers can be corrugated to increase the heat transfer surface area thereof or the surfaces may even be curved with the object in view of changing the cross sectional area of the flue from that which is here shown but yet providing a substantially constant cross sectional flue area throughout the entire flue passage.

It should be understood that the drawings and specification disclose the invention particularly in one embodiment thereof but that various modifications may be devised which will remain within the spirit and scope of the invention.

Having shown and described our invention, we claim:

1. A cylindrical boiler comprising transversely disposed interconnected water chambers and a flue passage of varying width extending between said chambers, the side walls of said passage being curved outwardly between the ends and a horizontal wall thereof being curved inwardly proportionately to said outward curvature of said side walls to diminish the depth of the passage commensurately with the increase in width thereof.

2. A cylindrical boiler comprising transversely disposed interconnected water chambers and a flue passage of varying width extending between said chambers, the height of said passage varying inversely to the width thereof from inlet to outlet to maintain a substantially constant cross-sectional area throughout the length of the passage.

3. A cylindrical boiler comprising transversely disposed interconnected water chambers and a flue passage of varying width extending between said chambers, said passage being of substantially uniform cross-sectional area from inlet to outlet but of maximum width and minimum depth at a point intermediate the ends thereof.

4. A cylindrical boiler comprising transversely disposed interconnected water chambers and a flue passage of varying width extending between said chambers, said passage

being of substantially uniform cross-sectional area from inlet to outlet but of maximum depth and minimum width in proximity to said inlet and outlet.

5. A boiler comprising a transverse flue 70 passage of varying width and a water chamber above said passage, the common wall between said chamber and passage being depressed to decrease the depth of said passage intermediate its ends commensurately 75 with the increase in width thereof.

In witness of the foregoing we affix our signatures.

CHARLES A. OLSON.
JOHN P. MAGOS.
